UNITED STATES PATENT OFFICE

FRANK CONNOLLY, OF TOLEDO, OHIO

VIGIL

Application filed April 25, 1930. Serial No. 447,366.

My invention has for its object to provide a decorative grave vigil that is so constructed that it will prevent extinguishing the candle flame by wind and rain.

5 The invention has particularly for its purpose to provide a means whereby lamps or candles may be burned within the marker and an effective light given off which increases the beauty of the general appearance of the 10 vigil.

The invention may be contained in grave vigils that vary in their form and construction and, to illustrate one form of the invention, I have selected a grave vigil as illustrative of the various embodiments of my invention and shall describe it hereinafter. The grave vigil selected is shown in the accompanying drawings.

Fig. 1 illustrates a perspective view of the 20 vigil. Fig. 2 illustrates a cross sectional view of the vigil. Fig. 3 illustrates a view of the vigil looking upward from the bottom. Fig. 4 illustrates a cross sectional view of the mesh end coverings of the cylinder.

25 The grave vigil 1 is formed of metal plate 5 having an outline that may be of any desired shape, such as the shape shown in Fig. 1. It may be cast in iron and gilded or painted, as desired, and have on its face such designs as 2 in bas-relief. The plate 5 has an opening 3 in any desired shape, preferably as shown, a heart shape, which is outlined by raised design of bas-relief, such as 4. Immediately behind the opening 3 is a chamber 6, whose walls 7 extend at right angles to the plate 5. A plate of transparent material, such as glass, may be set in the chamber 6, and against the opening 3, and there sealed in a manner well known in the art.

40 A cylinder 10 is attached to the walls 7 of the chamber 6 and is formed of a wall 16 of sheet metal. At the point of connection of the cylinder 10 and the chamber 6 an opening 18 is cut substantially of the same shape as the chamber 6. The bottom 12 of the cylinder 10 is covered by a closely woven net material, such as the wire mesh 13, having a series of openings 14. The openings 14 are formed in the wire mesh 13 by punching 45 holes outwardly, leaving the severed strands

21 caused by the operation, protruding outwardly and toward each other. The mesh is attached to a supporting metal ring 15 by soldering. The ring 15 is U-shaped in cross-section, and has a flange 17 which extends 55 around the bottom edge of the wall 16 of the cylinder 10 to tightly seal the ring 15 to the wall 16 of the cylinder 10. Uprights 19 are welded to the bottom of the web of the U-shaped ring member 15 and extend up into the chamber 10 to a point substantially in alignment with the opening 18 of cylinder 10. A ring 20 is connected to the two upright members 19.

60 A container 22, preferably of glass which may be colored as desired, having slanting walls 23 is adapted to telescopically fit the ring 20 and be supported thereby at a point substantially in alignment with the opening 18 of the cylinder 10 and the opening 3 of the plate 5. A candle 25 may be held in the container 22. The top end 24 of the cylinder 10 is covered by a net, such as the wire mesh 27, having a series of openings in the same manner as the bottom covering. The mesh 27 is connected to a ring 26. The ring 26 has a U-shaped cross section with an extending flange 28 at its circumference which is adapted to fit over the wall 16 of the cylinder 10 and tightly enclose the wall.

65 I have provided, therefore, a covering which allows for the entrance of air as it is used by the candle flame, but at the same time prevents the entrance of insects which will necessarily be attracted by the light, the projecting strands of wire of the larger openings providing obstacles to the entrance of such insects. The wire mesh also serves to break up and distribute and swift current of air which might extinguish the light by its concentrated force.

70 An L-shaped arm 30 is attached to the plate 5 at a point just above the top opening 24 of the cylinder 10. It may be attached to the plate by a screw 31. At the other end of the arm is connected a bell shaped cap 32 which substantially canopies the top opening 24 of the cylinder 10. Thus, it will be seen that I have provided a protecting shield to 75 the candle and at the same time allow for 80

the entrance of the required amount of air through the wire mesh, which also allows the heat generated by the flame to escape.

I claim:

- 5 In a grave vigil, a metal plate having a symbolical shaped opening, a cylinder connected to the plate and located behind the opening, a pair of mesh discs, one of the said pair of meshed discs located over the lower end of the cylinder, a receptacle for containing a wax-like material and a wick, the first named disc having uprights, a collar connected to the uprights for supporting the receptacle behind the opening, the other of said pair of discs having centrally located perforations, portions of the mesh adapted to extend over the perforations, the second named disc located over the upper end of the cylinder, a canopy attached to the plate and supported above the second named disc for covering the upper end of the cylinder.
- 10
- 15
- 20

In witness whereof I have hereunto signed my name to this specification.

FRANK CONNOLLY.
